UNITED STATES PATENT OFFICE.

WILLIAM H. H. GORHAM AND CHARLES R. GORHAM, OF CLEVELAND, OHIO, ASSIGNORS TO THE GORHAM MANUFACTURING COMPANY, OF CLEVELAND, OHIO, A CORPORATION OF OHIO.

VENDING-MACHINE.

No. 868,773.

Specification of Letters Patent.

Patented Oct. 22, 1907.

Application filed October 26, 1906. Serial No. 340,614.

To all whom it may concern:

Be it known that we, WILLIAM H. H. GORHAM and CHARLES R. GORHAM, citizens of the United States, residing at Cleveland, in the county of Cuyahoga and 5 State of Ohio, have invented a certain new and useful Improvement in Vending-Machines; of which the following is a full, clear, and exact description, reference being had to the accompanying drawings.

This invention relates to a coin controlled vending 10 machine. The machine is well adapted for embodiment in a machine for vending envelops. It includes suitable mechanism for ejecting the envelops, operating mechanism therefor, and mechanism for guiding a coin so as to enable the operating mechanism to operate the 15 ejecting mechanism.

The invention is illustrated in the drawings hereof and is hereinafter more fully described and its essential characteristics set out in the claims.

In the drawings, Figure 1 is a perspective view of 20 the vending machine complete; Fig. 2 is a plan showing the ejecting mechanism, the top plate of such mechanism being removed; Fig. 3 is a vertical section through such ejecting mechanism, substantially along the line 3—3 of Fig. 2; Fig. 4 is a perspective view of the envelop guides and the ejecting plunger and its guides; 25 Fig. 5 is a vertical section through the casing of the machine, showing the coin guide; Fig. 6 is a vertical section through the ejecting mechanism along the central line thereof as indicated by 6 in Fig. 2. Figs. 7 and 8 30 are fragmentary cross-sections on the lines 7—7 and 8—8, respectively of Fig. 4.

Referring by reference letters to the embodiment shown in the drawings, A represents a cabinet adapted to contain the envelops to be vended. This cabinet 35 has preferably a glass front *a* through which the envelops are visible, the bottom envelops being arranged to be ejected through a slotted guard *a'* carried by this front. The envelops are guided by suitable vertical rods B B' and are maintained in a compact pile by a 40 pressure plate C which rests on top of the envelops and is guided by the rods B. The envelops themselves are designated Z. At some convenient point, as at the top of the cabinet, is a mouth piece D for the coin chute. At another convenient point, preferably near the bottom, 45 is an operating plunger E.

The parts so far described are visible from the exterior of the cabinet, as shown in Fig. 1. Access to the interior of the cabinet may be provided in any suitable manner, for example, one of the sides may be hinged, 50 as indicated at *a*³, and provided with a suitable lock *a*⁴.

We have referred to the rods B B' which guide the envelops. These rods are preferably placed so that two of them guide the ends of the envelops and two of them the rear side thereof. As shown, the rods B are 55 secured at their lower ends to a suitable base plate G,

which may be of wood and preferably stands on the bottom of the cabinet. A short distance above this base plate is a plate F which is rigidly mounted on the rods B. Near its rear corners this plate is supported by standards I rising from the base plate G. The rods B' 60 are secured at their lower ends to the plate F and the upper ends of the four rods B and B' are secured to a top plate H, which has at its forward end a down-turned flange *h* by which the plate may be secured to the front side of the cabinet above the glass front. 65

On the underside of the plate F at the ends thereof are a pair of guide-ways formed by strips *f* and *f'* carried on such underside, the strips *f'* projecting farther inward than the strips *f*. Beneath the plate F is a plunger-plate J which has at its ends ears *j* occupying guide 70 ways provided by the strips *f* and *f'*. At its forward edge the plate J is provided with fingers *j'*. The envelops are adapted to rest upon the plate F with their flaps downward and occupying the triangle space in front of the plunger fingers and the supporting fingers 75 *f*³ carried by the plate F between the plunger fingers, these various fingers being cut back diagonally toward a central point to provide a space corresponding to the shape of the flaps.

The envelops are placed in the machine with the 80 flaps of two successive envelops nesting together, as shown in Fig. 4. When the plunger is caused to move forward as hereinafter explained, the fingers *j'* engage the flaps of the bottom two envelops and, shove such two envelops out through the exit slot in the guard *a'*, 85 where they may be grasped by the operator, this guard having a suitable depression *a*⁵ for the accommodation of one's thumb and first finger.

To cause the plunger to properly eject the envelop, it is given a downward movement as it moves forward, 90 thus grasping the flap between the plunger fingers and the plate M extending across the mechanism directly beneath the forward portion of those fingers, being carried by the plate F on the under side of its forward extensions. This downward movement is caused by 95 a downward bend in the guide-way which the ears *j* occupy as shown in Fig. 8.

To prevent the envelops being surreptitiously abstracted, the upper surface of the plate F is above the slot through the ejection guard. The downward movement of the plunger not only brings the envelop into position behind the ejection slot but grasps the envelop between the fingers *j'* and the plate M to insure the ejection. The fingers are made of thin material and are in the nature of leaf springs, wherefore when 105 they bear down on the plate M and efficiently grasp the flap, the openings between the stationary fingers *f*³ provide space to allow the fingers *j'* to normally stand with their upper edges (which may be turned upward, as at *j*³) nearly on a line with the upper surface of the 110

plate F. This insures the fingers j' entering between the flap and body of the envelop.

To give the plunger plate J its forward movement, we have provided the following mechanism: Pivoted 5 to the plunger plate is the link K connected at its rear end with the lever K'. Between such point of connection and the pivotal support K⁶ of this lever a link K² runs to the end of a lever K³ which is pivoted on a stud K⁴ rising from the base G, this stud being braced 10 by the bracket K⁵. The levers K' and K³ are each shown as constructed of a pair of bars, one above the other, to give the requisite stiffness and to allow the links to be conveniently connected by extending between the respective bars. Suitable distance sleeves 15 surround the pivot studs for these levers and maintain the bars in proper position.

The lever K³ is connected with a sliding rod L by the pin k' extending through a slot l' in a head l on the rear end of the rod, this rod being guided in a suitable 20 bracket L' carried to the base plate. The result of this leverage is that if the rod L be shoved rearward, the plunger J is thereby moved forward. A spring N connecting at its rear end to the lever K³ and at its forward end to a stationary point, tends to maintain the 25 plunger in its rearmost position.

At the forward end of the machine is a bracket P having a tubular bore whose axis is substantially in line with the axis of the rod L. In this bore is slidably mounted a tubular head or plunger E' which is 30 open at its rear end and at its front carries the operating plunger E. Surrounding the head E' and within the tubular bore of the bracket is a spring Q bearing at one end against a flange e on the head and at the other end against a flange p in the bore of the bracket. In 35 the normal position of the parts, if the plunger E be pressed rearward, the tubular head E' simply slides idly over the rod L and no operation takes place. If, however, a coin of the proper size be between the head and rod, it prevents the head sliding over the rod and 40 the rearward movement of the plunger will move the rod rearward to force the envelop plunger J forward, ejecting the envelop.

The coin chute is arranged to deliver a deposited coin between the head E' and the rod L. This coin 45 chute comprises a mouth piece D in which the coin is inserted; a tubular guide D' with which the mouth piece communicates and which as shown is secured to the inner side of one of the walls of the cabinet, and a guide way D² which is mounted on the bracket P 50 and into which the guide D' discharges. This guide way D² leads to a point directly at the rear of the head E'. At this point, the side walls terminate. There is however, a bottom wall p', which may be a portion 55 of the bracket P and which operates to support the coin, and a top wall d² which contracts the passage-way, preventing the escape of the proper coin but allowing a smaller coin to roll past the head E'.

Beneath the head E' and the rod L is a space G' provided by the removal of a portion of the base plate G 60 and this space may accommodate any suitable receptacle (not shown) for receiving the deposited coins. The mouth piece D does not allow the insertion of too large a coin. If too small a coin is inserted, it simply rolls idly past the head E' and drops into the coin receptacle. When the proper sized coin is inserted, it 65

comes to rest directly between the head E' and the rod L and forms a bridge across the end of the tubular head, allowing a rearward movement of the plunger to operate the ejecting mechanism to eject the envelops.

70

When the proper coin has been deposited and the operating plunger E moved rearwardly to eject the envelop, the coin is moved rearwardly between the head E' and the receding rod L. Just before the envelop reaches a point where it may be grasped by the 75 operator, the coin passes across the nose of the pivoted gravity pawl R carried by the bracket R' secured to the bracket L'. The coin passes idly over this pawl but on the return movement of the operating plunger, after the envelop has been ejected, the coin catches 80 on the rear face of the pawl nose and is thereby prevented from returning to position, and, as the head E returns, the coin is tipped over the pawl nose and drops by gravity into the coin receptacle.

It will be seen from the above description that no 85 operation can take place until the proper coin has been inserted and, before the operation has been carried far enough to eject an envelop, the coin is grasped and its deposit in the coin receptacle is insured. It is thus impossible to cause the ejection of more than 90 one set of envelops by successive movements of the plunger with the same coin.

The coin controlled operating mechanism shown herein and above described is not claimed herein but in our divisional application No. 392,887 filed Septem- 95 ber 14th, 1907.

As an extra precaution against picking the machine, we provide a dog S which is pivoted to the under side of the plate M and has a nose s normally extending through an opening m in this plate M in front of the 100 lowermost envelops and across the ejection slot. When this dog is in this position, it is impossible for envelops to be passed out through the slot. The dog is connected by a wire or link S' with the operating levers—as shown, with one of the levers K³. As this arm of the 105 lever moves rearward, in the first part of the operation, the dog is swung to withdraw the nose from the path of the envelops, as illustrated by Fig. 6.

The machine may be arranged to eject, as desired, one or more envelops for each coin deposited. When 110 stamped envelops are vended bearing two cent stamps, the machine may be arranged to operate upon the deposit of a five cent piece or nickel. In such case, the envelops are placed in the machine in sets of two each, with the flaps meeting as shown in the drawing 115 herein. This insures two envelops being ejected at the same time. The machine may with equal efficiency operate with coins of higher value and eject a corresponding number of envelops—for example, three or four envelops for a dime.

120

Having described our invention, we claim:

1. The combination of a plate for supporting envelops, a plunger-plate beneath the same, guideways for the edges of said plunger-plate, means for moving the plunger-plate forward into the space between the body of the envelop and the flap, and a stationary plate toward which said guideways bend and against which the plunger-plate may bind the flap.

2. The combination of a support for envelops having a space in front thereof which the flap of the lowermost envelop or envelops may occupy, a plunger plate beneath the

125

130

- support and normally behind such space, and means for moving said plate forward and downward into coöperation with another member to grasp the lowermost envelop or envelope and cause their ejection.
5. 3. The combination of a horizontal supporting plate, an ejecting plate suitably guided on the underside of the supporting plate, spring fingers on the forward edge of the ejecting plate, openings in the supporting plate which such fingers occupy, a clamping plate, and means for moving the ejecting plate forward to cause the fingers to enter between the flap and body of the bottom envelop, and means for guiding said ejecting plate to give it a diagonally downward and forward movement after such engagement to cause it to clamp the engaged envelop.
10. 10. The combination of a horizontal supporting plate, ejecting plate suitably guided on the underside of the supporting plate, spring fingers on the forward edge of the ejecting plate, openings in the supporting plate which such fingers occupy, a clamping plate, and means for moving the ejecting plate forward to cause the fingers to enter between the flap and body of the bottom envelop, and means for guiding said ejecting plate to give it a diagonally downward and forward movement after such engagement to cause it to clamp the engaged envelop.
15. 4. The combination of a horizontal supporting plate, vertical guides, an ejecting plate suitably guided on the underside of the supporting plate, fingers on the forward
- edge of the ejecting plate, openings in the supporting plate which such fingers occupy, a clamping plate, and means for moving the ejecting plate forward to cause the fingers to enter between the flap and body of the bottom envelop, and means for guiding said ejecting plate to give it a diagonally downward and forward movement after such engagement to cause it to clamp the engaged envelop, and an ejection guard having an opening below the top surface of the supporting plate.

In testimony whereof, we hereunto affix our signatures in the presence of two witnesses.

WILLIAM H. H. GORHAM.
CHARLES R. GORHAM.
